United States Patent Office.

ELISHA TURNER, OF WOLCOTTVILLE, CONNECTICUT.

Letters Patent No. 98,209, dated December 21, 1869.

IMPROVED CORD-TIGHTENER FOR CURTAIN-FIXTURES.

The Schedule referred to in these Letters Patent and making part of the same.

To all whom it may concern:

Be it known that I, ELISHA TURNER, of Wolcottville, in the county of Litchfield, and State of Connecticut, have invented and made a new and useful Invention in Cord-Tighteners for Curtain-Fixtures; and I do hereby declare the following to be a full, clear, and exact description of the said invention.

Cord-tighteners for curtain-pulleys have before been made, with the pulley fitted in a slide having ratchet-teeth, into which a tongue or pawl upon the pulley-block passes, to hold the pulley to any point at which it may be placed in tightening the cord.

My invention consists in a slide, for the pulley, formed with a series of holes through the thin sheet-metal of which the said slide is composed, the said slide being raised at the back part by means of ribs along the edges, in order that the projection upon the block of the pulley, in entering the said holes, may not come against the surface of the window-casing to which the cord-tightener may be applied.

In the drawing—

Figure 1 is an elevation of the said cord-tightener; Figure 2 is a vertical section of the same; and

Figure 3 is a horizontal section at the line $x x$.

a represents the surface of the window-casing or other place of attachment of the cord-tightener.

b is the sheet-metal slide formed with the returned

edges 1 1, between which the block c , carrying the pulley d , slides.

The back of the slide b is made with the ribs 2 2 at the edges, so that the centre portion of the slide at the back is kept away from the surface a , and in this centre portion of the back, holes, 3 3, are formed, and upon the block c is a projection, 4.

When the cord to the pulley is strained, the projection is kept into one of the holes 3, the block c , rocking in its slide by the strain of said cord; but the projection 4, although passing through the hole, does not come into contact with the surface or casing a .

This construction allows the cord to be slackened when necessary, as the block c can be rocked to throw the projection 4 out of the hole 3.

What I claim, and desire to secure by Letters Patent, is—

The slide b , formed with the ribs 2 2, at the edges of the back, and the holes 3 3 in the raised portion of the back, in combination with the block c , pulley d , and projection 4, as and for the purposes set forth.

In witness whereof, I have hereunto set my signature, this 8th day of October, A. D. 1869.

E. TURNER.
